UNITED STATES PATENT OFFICE.

RUSSELL HUFF, OF DETROIT, MICHIGAN, ASSIGNOR TO PACKARD MOTOR CAR COMPANY, OF DETROIT, MICHIGAN, A CORPORATION OF MICHIGAN.

PRESSURE-PUMP.

1,160,411.

Specification of Letters Patent

Patented Nov. 16, 1915.

Original application filed September 2, 1909, Serial No. 515,885. Divided and this application filed June 28, 1911. Serial No. 635,881.

To all whom it may concern:

Be it known that I, RUSSELL HUFF, a citizen of the United States, and resident of Detroit, Wayne county, State of Michigan, 5 have invented certain new and useful Improvements in Pressure-Pumps, of which the following is a specification.

This application is a division of my application, Serial No. 515,885, filed September 10 2, 1909.

This invention relates to pressure pumps and more particularly to an automatic cam-operated, air compressing pump for use in pressure systems. This pump is especially 15 adapted for use in connection with the gasoline tank of a motor vehicle, to which it supplies pressure, and it is so constructed as to be driven by the cam shaft of the motor of said motor vehicle.

20 The object of this invention is to provide an efficient, automatically operated pressure pump, mounted upon the crank case of a hydrocarbon or other motor, in an accessible position and adapted to be driven by the 25 cam shaft of the motor which is within the crank case.

It is also the object to provide a construction of such a character that all of the parts may be easily placed in position or removed 30 without disturbing the cam shaft or any of the other parts of the motor, and in which the liability of misassembly of the parts is practically eliminated.

In the drawings: Figure 1 is a vertical 35 section of the pump taken on the line 1—1 of Fig. 3; Fig. 2 is a view of the pump partly in elevation taken on the line 2—2 of Fig. 3; and Fig. 3 is a plan view of the pump.

Referring to the drawings: 25 represents 40 a part of the motor crank case upon which the pump is mounted.

26 is the cam shaft of the motor having fixedly mounted upon it the eccentric cam 27.

The connecting rod 28 provided with the 45 eccentric strap 45 cut away as shown at 46, 46, imparts motion from the cam 27 to the piston 34. This cut away portion is of sufficient size so that the eccentric strap 45 can be removed from the shaft by moving 50 the same endwise until it clears the eccentric 27, and then moving the same vertically. The connecting rod 28 is connected to the

piston 34 by the usual wrist-pin 47 held in place by the spring band 48.

The cylinder in which the piston 34 works 55 is externally threaded and is closed by a cylinder head 35 which is provided with an internal thread engaging the thread on the cylinder.

A lock nut 35' is provided for locking the 60 head in place.

The cylinder head is provided with a transverse passage 36 which may be formed therein in any suitable manner, preferably by boring the same, the hole being closed by 65 a plug 36'. An outlet passage 37 intersects the passage 36 and connects with the pipe line 23 in any suitable manner, preferably by the ordinary union joint, as shown. A spring-controlled check valve 38 70 controls the connection between the passage 36 and the cylinder. A relief valve casing 39 is screwed into the cylinder head and is provided with a relief valve 40 controlled by a spring 41, the tension of the spring 75 being controlled by an adjusting screw 42. A pipe 42' connects the cavity above the relief valve with the crank case 25. The cylinder is provided on its interior surface with a groove 43 which throws the crank case 80 into communication with the upper part of the cylinder when the piston is in its lowest position, the communication however being cut off when the piston passes the end of the groove, as shown in Fig. 2. The base 30 85 is provided with downwardly extending portions forming guides 44 for the connecting rod 28. The base 30 forms one of the cylinder heads.

It will be seen that the pump is of such 90 a construction that the parts may be easily assembled. The guides 44 are in offset relation to the axis of the cylinder and so guide the connecting rod that the pump is not affected by giving to the cam shaft 26 the 95 usual axial movement for the purpose of relieving compression in the cylinders of the motor in starting. In hydrocarbon motors it is desirable to reduce the distance between the cam and crank shafts to a minimum in 100 order to have the gears which drive the cam shaft of small size, and as a result there is very little space in which to operate the pump eccentric and the eccentric strap

thereon. In order to prevent the eccentric strap 45 from interfering with the connecting rods or cranks of the motor and also to permit the pump to be removed without disturbing the cam shaft 26 the eccentric strap 5 is cut away between the points 46, 46, this cut-away portion, as will be seen from Fig. 1, being slightly offset relative to the axis of the pump cylinder. On account of the 10 minimum clearance between the parts of the motor and the pump it is absolutely essential that the eccentric strap be placed in its proper position on the eccentric because otherwise the motor cranks would interfere 15 with the eccentric strap when the motor was started. In order, therefore, to eliminate all liability of misassembly of the parts the guides 44 are arranged in offset relation to the axis of the cylinder and the portion 20 28 of the connecting rod which cooperates with the guides is also offset so that it will be impossible to assemble the parts with the eccentric strap in other than its correct position on the eccentric 27.

25 The entire pump may be disassembled and disconnected from the valve shaft in the following manner: The bolts extending through the ears 33 are removed and the cylinder 32 is removed from the piston by 30 an endwise and upward movement. The piston is now removed from the connecting rod 28 by removing the band 48 and the wrist pin 47. The base 30 is now removed from the connecting rod, and the connecting 35 rod is moved to the left until the strap 45 clears the eccentric 27, and then moved upwardly, the opening formed in the strap 45 clearing the shaft 26. The valve shaft 26 must be moved to the position shown in Fig. 40 2 in order that the strap 45 may clear the eccentric 27. In order to insure that the parts 30 and 32 may be correctly positioned each of said parts is provided with three ears 31 and 33, respectively, and the crank 45 case is provided with three tapped holes for receiving the bolts extending through the ears.

The operation of the device is as follows: When the piston 34 descends, air is drawn 50 into the upper part of the cylinder through the groove 43 and upon the return of the piston this air is so compressed as to be forced out through the valve 38 into the passage 36 and then upward and out of the 55 pipe 37. In case too much pressure is evolved the excess may escape through the relief valve 40 and pipe 42 back into the crank case.

I claim:

60 1. In a pump, the combination with a casing, of a cylinder carried by the casing, a piston working in the cylinder, an operating shaft mounted in the casing, an eccentric on said shaft, and a connecting rod 65 provided with an eccentric strap formed

integral therewith and cut-away to clear the shaft, whereby the cylinder, piston and connecting rod may be removed from the casing without disturbing said shaft.

2. In a pump, the combination with a cylinder, of a piston working therein, actuating means, a connecting rod having loose and separable connection with said means, and a cylinder head provided with guides for the connecting rod and detachably connected to the cylinder. 70

3. In a pump, the combination with a cylinder, of a piston working therein actuating means, a connecting rod having loose and separable connection with said means, a one-piece cylinder head provided with guides for the connecting rod and detachably connected to the cylinder, and a detachable connection 80 between the piston and connecting rod.

4. In a pump, the combination with a cylinder, of a piston working therein, an operating shaft, an eccentric thereon, a connecting rod provided with an eccentric strap cut away to clear the shaft, a one-piece cylinder head provided with guides for the connecting rod and detachably connected to the cylinder, and a detachable connection 90 between the piston and connecting rod. 85

5. In a pump, the combination with a casing and a shaft mounted therein, of an eccentric on said shaft, a cylinder mounted on said casing, a piston for said cylinder, a connecting rod, and a guide for the connecting rod having an opening therein offset from the axis of the cylinder, said connecting 95 rod having a portion thereof adapted to be arranged in said opening, whereby the guide and connecting rod can be assembled in but one relative arrangement. 100

6. In a pump, the combination with a 105 casing having a cylinder mounted thereon, of a piston working in said cylinder, a head for said cylinder provided with a passage, an outlet connected to the passage, a connection between the cylinder and the passage, 110 a check valve in said connection, a relief valve for the passage, a pipe connecting the relief valve with the interior of the casing, and said cylinder having a passage extending longitudinally thereof and adapted to 115 connect the interior of the cylinder with the interior of the casing.

7. In a pump, the combination with a cylinder, of a piston working therein, a connecting rod, and a cylinder head detachably 120 connected to the cylinder and provided with guides for the connecting rod arranged in offset relation to the axis of the cylinder, for the purpose described.

8. In a pump, the combination with a cylinder, of a piston working therein, a connecting rod, a cylinder head detachably connected to the cylinder and provided with guides for the connecting rod arranged in offset relation to the axis of the cylinder, 125 130

and a detachable connection between the piston and connecting rod.

9. In a pump, the combination with a cylinder, of a piston working therein, an operating shaft, an eccentric on said shaft, a connecting rod provided with an eccentric trap having a cut-away portion adapted to permit the strap to be removed from said shaft laterally, a cylinder head detachably

connected with the cylinder, and a detachable connection between the piston and connecting rod.

In testimony whereof I affix my signature in the presence of two witnesses.

Copies of this patent may be obtained for five cents each, by addressing the "Commissioner of Patents, Washington, D. C."

It is hereby certified that in Letters Patent No. 1,160,411, granted November 16, 1915, upon the application of Russell Huff, of Detroit, Michigan, for an improvement in "Pressure-Pumps," an error appears in the printed specification requiring correction as follows: Page 3, line 7, claim 9, for the word "trap" read *strap*; and that the said Letters Patent should be read with this correction therein that the same may conform to the record of the case in the Patent Office.

Signed and sealed this 14th day of December, A. D., 1915.

[SEAL.]

R. F. WHITEHEAD,

Acting Commissioner of Patents.
